UNITED STATES PATENT OFFICE.

ANTON RUZICKA, OF CLEVELAND, OHIO.

MACHINE FOR MAKING PRESS STUDS OR FASTENERS.

Application filed July 13, 1917. Serial No. 180,368.

To all whom it may concern:

Be it known that I, ANTON RUZICKA, a citizen of the United States, residing at Cleveland, in the county of Cuyahoga and State of Ohio, have invented certain new and useful Improvements in Machines for Making Press Studs or Fasteners, of which the following is a specification.

This invention relates to machine for making so-called press studs or fasteners which consist of a head part and a socket part, the head part having small heads or studs provided with slots at the sides, and the socket part having a bent spring which snaps over the heads and into the slots when the parts are pressed together, and which permit the parts to be separated by slight pull when it is desired to unfasten the same. The present machine is intended particularly for the continuous and rapid production of the head parts of the fastener, and includes means for pressing, punching and slotting the said parts as will more fully appear from the following description and the accompanying drawings.

In the drawings, Figure 1 is a side elevation showing the devices as mounted in a press.

Fig. 2 is an end elevation of the same. Fig. 3 is a plan of the bed over which the work is fed.

Fig. 4 is a section on the line 4—4 of Fig. 1.

Fig. 5 is a vertical section showing the dies in open position.

Fig. 6 is a similar section with the dies closed.

Fig. 7 is a vertical section on the line 7—7 of Fig. 4, in open position.

Fig. 8 is a vertical section on the line 8—8 of Fig. 4, with the parts closed.

Fig. 9 is a detail in section on the line 9—9 of Fig. 4, showing one of the studs in position.

Fig. 10 is a detail in section on the line 10—10 of Fig. 5.

Figure 11 is an end view of one of the die members.

Referring specifically to the drawings, 1 indicates a bed plate mounted on the base 2 of the press by means of clamps at the sides thereof. 4 is an upper die plate attached to the reciprocating cross head 5 of the press. The bed 1 comprises a lower piece 6 plate 7 and spacing blocks 8 forming a

recess 9 which extends the full length of the bed, under the punching and cutting devices. The base 6, plate 7 and blocks 8 are held together by screws 9^a and 10^a and studs 11. Rows of circular openings 18, 19, 20, 21, 22, 23, and 24 are cut through the plate 7 and are arranged in succession, the openings in each row being staggered as shown in Fig. 3, to avoid waste of stock, each row as shown consisting of five holes or openings, and enabling five studs to be made at the same time. This number of course can be varied as desired, and the openings constitute guide members for the punches.

These punches 25, 26, 27, 28, 29, 30, and 31, are mounted directly above and in line with the openings and are fixed to the lower plate 14 of the upper head 4, which plate is secured to the dovetailed plate 15 which fits in the slot 16 of the block 17 on the cross head 5.

Mounted in the base plate 6, below and in line with the openings 18 to 24 are the shaping and cutting bushings, or female die members, 32, 33, 34, 35, 36, 37, and 38, these being arranged in rows corresponding to the rows of punches and shaped to perform the successive operations to be described.

A cutter bar 39, having a recess 40 to provide room for the last row of bushings 38, is mounted for lateral movement in a recess 41 in the base 6, and mounted on this cutter bar are a series of pairs of knives 42 which are located in line with each line of studs and which act to cut the slots in the heads of the studs, one slot being located at each side of the head. See Fig. 9. The cutter bar 39 has slots 43 at each end containing rollers 44. These rollers co-operate with cam plungers 45 fixed to the head plate 14, and these plungers work through the slots 43 as well as through slots 46 in the plates 6, 7, and 8 and when the plungers descend they strike the rollers 44 and the cam surfaces thereof shift the cutter bar 39 and the knives carried thereby outwardly or toward the right hand end of the die plate as seen in Fig. 4.

When the plungers 45 are lifted the cutter bar is forced back by the spring plungers 47 located in recesses in the end of the bed plate. A slot 48 is cut through the bed plate to allow the cuttings to drop out. A thin plate 49 covers the recess 41 and the

cutter bar 39 serves to prevent the knives 42 from cutting the slots in the head of the stud to close to the base thereof. That is, this plate 49 serves to space the knives from the flat part of the work, the knives working under the plate and the flat strip or material passing over the plate, as shown in Fig. 9.

The base plate 6 is provided with spacing holes 50, between the bushings 35, 36, 37 and also beyond the recess 41. (See Fig. 5.)

The row of bushings or female die members 33 are pressed up by springs 51 thereunder acting to lift the strip of metal after each operation, to allow it to be moved forward or fed along for the next operation. The rows of bushings or die members 35, 37, and 38 are also provided with central spring pressed plungers 52, 53, 54, each of which will yield at each stroke of the press, and lift after each stroke to raise the strip of material so that it can be fed along. The punch or die members 25 to 30 have projections 55 corresponding in shape to the female recesses 56 in the bushings 32 to 37.

Ten successive operations are performed with this machine in making the studs. The strip of metal is fed through the slot 9 from the left hand end. Any suitable form of intermittent feeding device may be used, feeding the metal forward step by step. The first operation is performed by the row of dies 25 which make bosses or depressions in the strip corresponding to the depression 56 in the bushing 32. At the next operation this boss is deepened by the die 26 and the bushing 33, and at the next step the head or boss is elongated by the die 27 and bushing 34, and then further shaped and narrowed by the die 28 and bushing 35, the plunger 52 yielding as shown in Fig. 6. The next operation is simply to space, the heads of the studs being received in the spacing holes 50. At the next operation the punch 29 punches holes through the base of each member by means of cutters 29^a and appropriate holes in the bushing 36, the punchings dropping out through the passage in the base plate. The next operation is a space. The next operation flattens the metal, to correct any upset burs caused by the cutters 29^a, the flattening being effected by the die 30 and the bushing 37, the latter having a yielding plunger 53. The next operation is a space, and the last operation is the cutting of the grooves in the sides of the heads by means of the knives 42 and bar 39 which is reciprocated by the cams 45, and at this operation the studs are engaged by the die members 31 co-operating with the bushings 38.

As shown in Fig. 10 each of these die members has the plunger 60 mounted therein and depressed from above by a spring 61. The plunger 60 has a longitudinal groove 62 engaged by a projection 63 which keeps the plunger from turning, and at the end the

plunger has a projection 64 which is wider one way than the other, or flattened on the sides, and this projection 64 enters the head of the stud and forces it down against the plunger 54 in the bushing 38, and the flattened sides of the projection 64 provide a space permitting the knives 42, when they advance, to cut through the head at each side thereof. It will be understood that the spring pressed plungers in some of the bushings lift the stock clear of the female dies after each operation, so that the strip can be advanced by the feeding mechanism after each operation. This machine operates in the manner above described to shape and cut the studs in a strip of metal, from which they can afterwards be individually cut and finished by other machines.

I claim:

1. In a die press, the combination with a die mechanism adapted to form a boss on a strip of metal, of a pair of cutters movable in a line parallel to said strip and lengthwise thereof and adapted to cut a slot in each side of said boss.

2. The combination with a die press having members adapted to form bosses on a strip of metal fed between the same, of a reciprocating cutter bar extending across the line of feed of said strip and movable parallel to said line and provided with cutters adapted to cut slots in opposite sides of said bosses.

3. The combination with a die press having fixed and movable press parts provided with die members adapted to form successive bosses on a strip of metal fed between the same, of a reciprocating cutter bar mounted in a recess in the fixed press part and extending across the line of movement of said strip and provided with cutters adapted to cut slots in the sides of said bosses, and means carried by the movable press part to operate the cutter.

4. The combination with a die press having a bed provided with a female die member and a reciprocating head provided with a male die member, of a reciprocating cutter bar working in a recess in the bed in a direction at a right angle to the axis of the dies and provided with cutters adapted to act on work after it passes said dies, and means carried by the reciprocating head to operate said cutter bar.

5. The combination of a die press bed having a transverse recess, a reciprocating die head co-operating therewith, a cutter bar movable in said recess in a plane parallel to the face of the bed and having cutters adapted to act on projections on work passing across said bed, and means to operate the cutter bar, said means including a cam carried by said head and engaging the cross bar to move the same one way, and a spring to move the same the other way.

6. The combination with a bed plate having a recess, of a face plate over said recess and having an opening through which a boss on a piece of work on the face plate may project into said recess, of a cutter working laterally in said recess under said face plate and adapted to slot the side of said boss, and means to operate said cutter.
7. The combination with a pair of die members one of which has a recess and a face plate over said recess, said plate having an opening through which a boss on a piece

of work may be pressed by the other member of a cutter working in said recess under said plate and adapted to slot the side of 15 said boss while it is projecting through the opening, and means to operate the cutter in time with the die members.

In testimony whereof, I do affix my signature in presence of two witnesses.

ANTON RUZICKA.
